DESIGN FOR A LAMP

Earl S. Boynton, East Orange, N. J.

Application June 17, 1947, Serial No. 139,747

Term of patent 14 years

(Cl. D48—20)

To all whom it may concern:

Be it known that I, Earl S. Boynton, a citizen of the United States of America, residing at East Orange, county of Essex, and State of New Jersey, have invented a new, original, and ornamental Design for Lamps, of which the following is a specification, reference being had to the accompanying drawing, forming part thereof.

In the drawing:

Fig. 1 is a side elevation of a lamp, showing my new design;

Fig. 2 is a top plan view of the lamp shown in Fig. 1; and

Fig. 3 is an end elevation of the lamp shown in Fig. 1.

I claim:

The ornamental design for a lamp, substantially as shown.

EARL S. BOYNTON.
